COUPLING FOR PIPES OR THE LIKE

Leland S. Hamer, Long Beach, Calif.

Application July 28, 1949, Serial No. 4,176

Term of patent 14 years

(Cl. D91—3)

To all whom it may concern:

Be it known that I, Leland S. Hamer, a citizen of the United States, residing in the city of Long Beach, county of Los Angeles, and State of California, have invented a new, original, and ornamental Design for a Coupling for Pipes or the like, of which the following is a specification, reference being had to the accompanying drawings, forming a part thereof.

Fig. 1 is a perspective view of the coupling for pipes or the like, showing my new design, as viewed from the top, one end and one side thereof, Fig. 2 is a perspective view of the coupling, as viewed from the bottom, the other end and the other side thereof, and Fig. 3 is an end view of the coupling, being a view of the end shown in Fig. 1.

I claim:

The ornamental design for a coupling for pipes or the like, as shown.

LELAND S. HAMER.
